UNITED STATES PATENT OFFICE.

ANNA J. MOSS, OF COLLINGSWOOD, NEW JERSEY.

DESIGN FOR A BADGE OR SIMILAR ARTICLE.

40,560.

Specification for Design.

Patented Mar. 8, 1910.

Application filed January 6, 1910. Serial No. 536,777. Term of patent 14 years.

To all whom it may concern:

Be it known that I, ANNA J. Moss, a citizen of the United States, residing at Collingswood, in the county of Camden and State of New Jersey, have invented a new, original, and ornamental Design for Badges or Similar Articles, of which the following is a specification, reference being had to the accompanying drawing, forming part thereof.

The figure is a perspective view showing my new design.

The design in its entirety consists of a base A, on which are placed sticks B to represent a wood pile, and in this is placed a negro doll baby.

I claim:

The ornamental design for a badge or similar article, as shown and described.
